UNITED STATES PATENT OFFICE.

HARVEY B. WILSON, OF ATHENS, ILLINOIS.

RADIATOR GUARD.

Application filed November 11, 1925. Serial No. 68,317.

My invention relates to a class of devices that are adapted to be used for the protection of radiators of automobiles, tractors, and the like, an object being in this device 5 to simplify the character of the device and to provide details of construction whereby the guard may be made more substantial and may be manufactured more economically.

16 A particular object of my invention furthermore being to provide a radiator guard with the above merits and certain other features of construction providing durability and stability of mounting which will be 15 hereinafter more fully described in the annexed specifications, recited in the claims and illustrated in the accompanying drawings in which like reference numerals indicate the same structural parts in the several 20 figures:

Referring to the drawings: Figure 1 is a front elevation of the radiator guard of my invention.

Figure 2 is a perspective of the radiator 25 guard of my invention shown mounted on a radiator of a car.

Figure 3 is a detail of one of the brackets supporting the radiator guard of my invention.

20 Figure 4 is a detail of one of the rods of the radiator guard of my invention.

Referring now to the detailed elements 25 of construction in the device of my invention numeral —1— refers to one of the rods

serving as a guard for the radiator guard 30 of my invention. Numeral —2— indicates the lower bracket in which these rods are mounted. Numeral —3— indicates the upper bracket supporting the rods. Numeral

35 —4— indicates one of the cross brackets located near the middle of the radiator guard. Numeral —5— indicates one group 40 of rungs arranged in parallel position along the sides of the radiator guard of my invention and adapted to provide fastening means 45 for holding the cold weather shield in various elevations of adjustment. Numeral —6— indicates one of the holes in the bracket adapted to be used in fastening the bracket to the radiator. Numeral —7— indicates the hole on the opposite end from

numeral —6— in the same bracket. Numeral —8— indicates one of the holes adapted to accommodate the group of vertical rods serving as guards. Numeral —9— indicates one of the shoulders and numeral —10— another of the shoulders of the rods adapted to serve as stop means for the rod at the upper and lower end thereof.

It will be observed by those skilled in the art that a radiator guard of this character of construction is not only convenient to mount on a radiator but is adapted to be substantial in construction and durable and convenient to clean out in case corn stalks or other things get caught in between it and the radiator and it will be further observed that a device of this kind may be found useful not only on the radiator of automobiles but on tractors or any other movable motors.

Numeral —11— indicates the radiator on which the radiator guard would be fastened and numeral —12— indicates the bracket on such a radiator to which this radiator guard could be fastened.

It will be observed that when assembling this radiator guard that the shoulders —9— and —10— of the rods —1— provide stop means for the bracket and after the rod is fitted into the holes therefor in the bracket 80 the ends —13— and —14— of the rods are adapted to be riveted substantially to the brackets —2— and —3— respectively and it will therefore be seen that such a construction will provide a very substantial and 85 neatly designed radiator guard.

Having thus described the nature of my invention what I claim is:

1. In a radiator guard of the character described a pair of spaced parallel horizontally disposed brackets provided each with a plurality of perforations accommodating corresponding ends of a like number of upright rods; swaged shoulders spaced from each end of said rods providing stop means 90 therefor; a central bracing rib parallel with said brackets adapted to brace said rods in the middle and a plurality of spaced horizontal rungs secured between the two outer pairs of upright rods and between the inner pair of rods; whereby a cold weather shield 95 being mounted on a roller may be detachably 100

secured to the guard at different elevations of adjustment.

2. In a radiator guard of the character described having guards and brackets therefor, 5 a guard rod having a swedged shoulder near each end and a soft metallic tip beyond said shoulders whereby said rod may be suitably

riveted into holes in said brackets adapted to accommodate the same.

In witness whereof I hereunto set my ¹⁰ hand and seal this 17th day of September, 1925.

HARVEY B. WILSON.
